UNITED STATES PATENT OFFICE.

THEODORE G. LEWIS, OF BUFFALO, NEW YORK, ASSIGNOR TO BUFFALO DENTAL MANUFACTURING COMPANY, OF BUFFALO, NEW YORK, A CORPORATION OF NEW YORK.

DESIGN FOR A DENTAL MOLDING-FLASK.

45,842.

Specification for Design.

Patented May 26, 1914.

Application filed April 3, 1914. Serial No. 829,374. Term of patent 7 years.

To all whom it may concern:

Be it known that I, THEODORE G. LEWIS, a citizen of the United States, residing at Buffalo, in the county of Erie and State of New York, have invented a new, original, and ornamental Design for Dental Molding-Flasks, of which the following is a specification, reference being had to the accompanying drawing, forming part thereof.

Figure 1 is a front elevation of an orna-

mental molding flask showing my new design. Fig. 2 is a side elevation thereof. Fig. 3 is a rear view of the same.

I claim:

The ornamental design for a dental molding flask, as shown.

THEODORE G. LEWIS.
